CASEMENT WINDOW ADJUSTER

Ernest E. Weidner, New Haven, Conn., assignor
to The H. B. Ives Co., New Haven, Conn., a
corporation of Connecticut

Application February 21, 1934, Serial No. 712,364

2 Claims. (Cl. 292—275)

This invention relates to improvements in casement window adjusters adapted for use in connection with casement windows, transoms and all casement structures.

The objects of the invention are to provide a compact device requiring little space in installation; to provide an adjuster device having telescopically associated arms provided with a stop means to limit the relative extended positions of said arms; to provide said arms, intermediate of their length, with frictional inter-holding means of great efficiency in which there is no metal to metal contact; to provide said frictional inter-holding means with a spring tension adapted to also maintain the enclosed arm substantially friction free from the enclosing arm; and to provide, as between said arms and said frictional inter-holding means, a limited slipping engagement, longitudinally of said adjuster, to alleviate rigidity.

With these and other objects in view as hereinafter may become apparent from the within disclosures, the invention consists not only of the particular form herein pointed out and illustrated in the drawing, but readily admits of certain modification within the scope of what hereinafter may be claimed.

The character of the invention may be best understood by reference to one illustrative device illustrated by the accompanying drawing in which the Figure 1 is a top view of the device installed within a mortise of a casement window sash, the window frame being partly illustrated in cross-section; the Figure 2 is an enlarged fragmentary top view of the device, illustrating the enclosing arm partly in section to expose the frictional inter-holding means; the Figure 3 is a fragmentary bottom perspective view of the device, illustrating a stop means; the Figure 4 is a cross-section of the device on the dotted line "4—4" of the next previous figure; the Figure 5 is an enlarged cross-section of the device on a line extending through the frictional holding means; and the Figure 6 is another enlarged cross-section illustrating a modification of the stop means.

Referring more particularly to the drawing, the device as illustrated comprises the two telescopically associated enclosing and enclosed arms 1 and 2, respectively, the free ends of both arms being provided with the pivotal attaching means 3 and 4, respectively. The enclosing arm 1 is provided with the channel 5 extending substantially therethrough, and the enclosed arm 2, capable of being freely inserted within the enclosing arm 1, is preferably solid, but not necessarily so, and is

provided adjacent its inner end with oppositely located recesses 6 and 7, the length and depth of each recess being limited by the abrupt shoulders 8 and the base 9, respectively. The enclosed arm 2 is provided with the companion sets of a frictional element carried within the recesses 6 and 7. Said companion sets are thus placed upon opposite sides of the enclosed arm 2 and each set is comprised of a frictional shoe section 10, preferably of fibrous material and of less length than the distance between the shoulders 8 of either recess 6 or 7, and of a bow spring 11 positioned between said base 9 and the said section 10, both ends of the said spring 11 engaging a shoulder 8 and resting upon a base 9, while the intermediate convexed portion of the spring 11 engages the fibrous section 10. The tensions of the oppositely placed springs 11 of the companion sets are thus exerted in opposite directions, outwardly, to urge and maintain the respective sections 10 projected beyond the normal outer side surfaces 12 of the enclosed arm 2. The under surface 13 of the enclosed arm 2 is provided with the longitudinally extending groove 14 having the side walls 15. At a convenient and predetermined place within the groove 14 is provided an obstruction 17 formed by throwing up the metal of either or both side walls 15 into said groove 14 or in any other desired manner. Also at a convenient and predetermined place within the channel 5 of the enclosing arm 1 there is likewise provided the obstruction 18.

The fibrous shoe sections 10 and the springs 11 being placed within their respective recesses 6 and 7, as aforesaid, the arms 1 and 2 are telescopically associated, the outwardly spring-pressed fibrous shoe sections 10 being manually compressed therefor so that, when released from their manually compressed positions within the enclosing arm 1, they frictionally engage opposite interior side surfaces 16 of the channel 5 of the enclosing arm 1. In such frictional engagement the fibrous shoe sections 10 cause the springs 11 to maintain the opposite side surfaces 12 of the enclosed arm 2 out of direct frictional engagement with the opposite interior side surfaces 16 of the channel 5 of the enclosing arm 1. In telescopically associating the arms 1 and 2 it is better, for obvious reasons, that the obstruction 18 be formed after the insertion of the inner end of the arm 2 within the channel 5 of the arm 1.

In installing the device with relation to a casement window, a mortise 19, preferably in the top portion of a window sash 20, may be provided in which to completely contain and, with the cooperation of the meeting part of the frame 21, to

conceal the device, the pivotal attaching means 3 of the arm 1 being further mortised within the mortise 19, as at 23, and the pivotal attaching means 4 being mortised, as at 22, within an over-head portion (not illustrated) of the window frame 21, so that, in a closed position of the sash 20 within the frame 21, the arms 1 and 2 of the device are substantially fully telescoped.

In operating the sash 20 swung upon its hinges, 10 one of which is illustrated at 24, the telescoped arms 1 and 2 are relatively moved longitudinally to extend the reach of the adjuster device as the distance between the attaching means 3 and 4, as pivotally secured to the window sash 15 20 and the frame 21, is thereby increased until upon reaching a substantially ninety degree open position of the sash 20, relative to the frame 21, the obstruction 18 provided by the arm 1 is blockingly engaged by the obstruction 17 provided by the arm 2, such engagement serving as 25 a stop in limiting the extended relative movements of the arms 1 and 2. Between a fully closed position and said ninety degree open position, the frictional engagement between the spring-pressed fibrous sections 10 and the interior side surfaces 16 of the metal channel 5 of the arm 1 is of such a degree of efficiency that the manually swung window sash 20 is thereby held in any open position against a considerable 30 wind pressure. Upon a directional reversed movement of the swinging sash 20 provided with the improved adjuster device the frictional element has a multiple action in that each spring 11 is in frictional engagement with a fibrous 35 section 10 while each section 10 is in frictional engagement with the interior side surfaces 16 of the enclosing arm 1, therefore the fibrous sections 10 are not necessarily immediately carried by the recesses 6 and 7 of the enclosed arm 2 40 within the channel 5, but, similar to the action of the well-known multiple disk clutch, the springs 11 have a tendency to slip in the engagement of their convexed portions with the fibrous sections 10 until such sections 10 are 45 positively engaged by the shoulders 8 at one end or the other of the recesses 6 and 7. The obvious purpose of such multiple frictional engagement is to alleviate rigidity in the starting operation of the device; for, while in the starting operation the fibrous sections 10 may be moved to some extent, they are not fully carried by the enclosed arm 2 until the shoulders 8 at one end

of the recesses 6 and 7 are brought in direct engagement therewith. Before the sections are in direct carrying contact with the shoulders, the convexed portions of the springs 11 have a limited frictional traveling engagement with the sections 10. The great advantage of this improved starting operation as applied to window adjusters is not only the ease with which a window sash may be manually swung to or from any open position, but the improvement provides a very desirable yielding quality which tends to lessen the strain upon the hinges 24.

The Figure 6 illustrates a modification which transposes the preferred arrangement of the stop means for limiting the extended relative longitudinal positions of the arms 1A and 2A, the channelled enclosing arm 1A being provided with a groove 14A having the side walls 15A opposite portions of which are provided with the obstruction 17A and the solid arm 2A being provided with 20 the obstruction 18A adapted to travel within the groove 14A, the obstructions 17A and 18A being intended for relative blocking engagement in substantially the same manner as in the preferred structure.

I claim:—

1. A casement adjuster comprising telescopically associated rigid enclosing and enclosed arms, the free end of each arm having a pivotal attaching means, a frictional shoe device within the enclosing arm and carried by the enclosed arm to frictionally engage the enclosing arm, and a stopping means with which the adjuster is internally provided to limit the relative extending movement of the arms, said stopping means comprising a longitudinally extending channel with which one of the arms is provided, a projection on the wall of the channel and confined within the channel and a projection provided by the other arm and extending into the channel.

2. A casement adjuster comprising telescopically associated enclosing and enclosed arms, the free end of each arm having a pivotal attaching means, and a stopping means with which the adjuster is provided to limit the relative extending movement of the arms, said stopping means comprising a longitudinally extending channel with which one of the arms is provided, a projection on the wall of the channel and confined within the channel and a projection provided by the other arm and extending into the channel.

ERNEST E. WEIDNER.
